ANNEALING COVER

Gerald D. Stough, Detroit, Mich., assignor to
 Whitehead & Kales Company, River Rouge,
 Mich., a corporation of Michigan

Application June 4, 1951, Serial No. 229,845

8 Claims. (Cl. 263—49)

1

The present invention relates to an annealing cover.

In annealing steel the practice is to provide a movable platform provided with a suitable sealing material such as sand, above which are supported the sheets of steel to be annealed. The annealing cover generally comprises an enclosure having side walls, a top wall, and an open bottom. The cover is placed over the steel to be annealed with the bottom edges of the cover embedded in the sand or other sealing material, so as to provide a substantially sealed enclosure for the steel. A common practice is to carry out the annealing in a controlled atmosphere. The assembly is then moved into an annealing oven and is brought up to an annealing temperature as for example, about 1450 degrees Fahrenheit.

In the past considerable difficulty has been encountered in properly supporting the top of the annealing cover. This cover may be several feet wide and many feet long so that it tends to sag considerably, particularly when subjected to heat. The usual steel employed in making annealing covers loses a large part of its strength when it is heated to 1450 degrees Fahrenheit. Repeated use of annealing covers as known to the prior art, resulted in structural damage to the parts due to continued heating and cooling and presumably was largely traceable to strains set up by unequal expansion of the parts.

It is an object of the present invention to provide an annealing cover characterized by improved means for supporting the top wall of the cover.

It is a further object of the present invention to provide an annealing cover characterized by the provision of a plurality of elongated supporting members spanning the annealing cover directly below the top wall thereof, in position to support the top wall against sagging, the supporting members being slidably related to the top wall of the annealing cover.

It is a further object of the present invention to provide an annealing cover in which opposite side walls thereof are provided with inwardly facing opposed pairs of sockets and elongated supporting members having their ends slidably received in the sockets, the upper surface of the elongated members being disposed directly beneath the lower surface of the top wall of the annealing cover in position to support the same.

It is a further object of the present invention to provide an annealing cover comprising elongated supporting trusses for the top wall carried independently of the top wall directly beneath

2

the same to support the top wall against sagging.

It is a further object of the present invention to provide an annealing cover comprising a plurality of top supporting trusses formed of a material adapted to retain substantial strength under annealing temperatures.

It is a further object of the present invention to provide an annealing cover comprising top supporting trusses spanning a pair of opposed side walls directly beneath the top of the cover in which the ends of the trusses are supported by sockets in which the ends are slidable.

It is a further object of the present invention to provide an annealing cover including top supporting trusses which may be salvaged when the annealing cover is expended.

Other objects and features of the invention will become apparent as the description proceeds, especially when considered in conjunction with the accompanying drawings, wherein:

Figure 1 is a fragmentary top plan view of an annealing cover constructed in accordance with the present invention.

Figure 2 is a section on the line 2—2, Figure 1.
 Figure 3 is an enlarged section on the line 3—3, Figure 2.

Figure 4 is a section on the line 4—4, Figure 3.
 Figure 5 is an enlarged section on the line 5—5, Figure 2.

Figure 6 is a fragmentary elevational view of a modified form of truss.

Referring now to the drawings the annealing cover comprises side walls 10 and 12, and end walls 14. As seen in Figures 1 and 2, the side and end walls are preferably formed of corrugated sheet material such for example as mild steel and are inclined inwardly and upwardly at a small angle. The annealing cover includes a top wall 16 also formed of mild steel and this wall is preferably formed of flat sheet material. The edges of the side and end portions are interconnected by welding and the edge portions of the top 16 are welded to the top edges of the side and end walls 10, 12, and 14. Thus there is provided an enclosing cover which is air tight and which is adapted to keep atmosphere from steel products being annealed when the annealing cover is used as conventional in the art.

Efforts to reinforce the top wall 16 from sagging have proved unsatisfactory in past constructions and in general annealing covers have been relatively short lived since stresses set up by unequal expansion, and by sagging of the top wall of the cover, have destroyed the sealing capacity of the annealing cover.

In accordance with the present invention novel means are provided for supporting the top wall 16 and these means are supported entirely independently of the top wall so as to have relative sliding motion with respect thereto when unequal expansion or contraction takes place. Specifically, the top supporting means comprises trusses indicated generally at 20, herein shown as having reduced end portions 22 receivable in stirrups or socket supports 24.

Referring now to Figures 3, 4, and 5, the detail support for the truss members will be described. On the inner surface of the side walls 10 there are provided flat plates 26 which are welded, as indicated at 28, to the inner surface of the side walls as best illustrated in Figure 3. Generally U-shaped brackets 30 are in turn welded to the inner surfaces of the plates 26 with the upper ends of the brackets engaging the under surface of the top wall 16. Preferably, the top edges of the brackets 30 are also welded to the underside of the top wall 16. Thus, the brackets 30 cooperate with the plates 26 and the top wall 16 to provide open socket members. These members are provided in opposed pairs at opposite sides of the annealing cover.

The truss 20 includes an upper strip 32, a lower strip 34, and transverse bracing elements 36. Adjacent the ends of the truss the strip 34 is bent upwardly as indicated at 38 to provide a short section 40 closely adjacent to the upper strip 32. Intermediate the strip 32 and the section 40 of the lower strip 34 is a transverse web 42. The dimensions of the bracket 30 are such that the reduced end of the truss 20 fits freely therein, sufficient clearance being provided so that the ends of the trusses are freely slidable in the sockets or stirrups provided by the brackets 30. The parts are so dimensioned that the upper surface of the strip 32 is directly beneath the under surface of the top wall 16, in position to engage the wall and support it against sagging, particularly when the top wall is subjected to the relatively high temperatures prevailing in the annealing furnace.

Intermediate the side walls 10 and 12 of the annealing cover, there are provided abutments 44 which are welded or otherwise secured to the underside of the top wall 16 of the annealing cover. As best seen in Figure 5, the abutments 44 may be constituted by short sections of angle iron, one leg of which is welded to the under surface of the top wall 16. The depending legs of the angle iron are spaced apart to provide a small amount of clearance with respect to the upper strip 32 of the truss so that relative sliding may take place between the top wall 16 and the strip 32 as the parts expand or contract unequally upon heating and cooling. The abutments 44 have the function of preventing bowing or transverse curvature of the trusses 20.

In Figure 6 there is illustrated a modified form of truss comprising an upper member 50, a lower member 52, and diagonally extending brace sections 54. Again, the ends of the truss shown in Figure 6 are reduced as indicated generally at 55 for slidable reception in sockets of the type previously described.

For best results the top supporting trusses 20 are formed of a material adapted to retain a large part of its strength when heated to 1450 degrees Fahrenheit. For this purpose stainless steel is found to be entirely satisfactory. However, other less expensive materials are also suitable for this purpose.

A consideration of the drawings will of course

make it apparent that the trusses 20 are supported independently of the top so that each element of each truss is relatively slidable with respect to portions of the top directly adjacent thereto. Thus unequal expansion between the truss and top wall 16 sets up no stresses tending to damage or weaken the structure. Moreover, since the reduced end portions 22 of the trusses are slidable in the sockets 24 there may be very substantial differences in expansion and contraction between the annealing cover as a whole and the top supporting trusses 20 without subjecting the parts to stress.

It will be appreciated that it is not strictly necessary to obtain the advantages of the present construction to have both ends of the trusses slidable, since stresses will be avoided even though one end of the truss is permanently and rigidly secured to its supporting socket or the adjacent wall structure. However, it is convenient to support both ends of the trusses with the same construction.

In manufacturing annealing covers of the type disclosed herein it will be appreciated that the trusses must have their ends located in the bracket members 30 when these members are welded or otherwise secured to the plates 26 and the top wall 16. Thus, the truss is not removable from the annealing cover during its useful lifetime. However, it is found that the top and side walls of the annealing cover deteriorate after extended usage. At this time the trusses 20 remain in perfectly usable condition and accordingly the present construction makes it possible to salvage the trusses by simply removing the brackets 30 so that the trusses may be incorporated in additional annealing covers.

While the brackets 30 have been illustrated and described as welded both to the top edge portions of the side walls 10 and 12 and the underside of the edge portions of the top wall 16, it will of course be appreciated that the brackets 30 could be secured to the side walls 10 and 12 independently of the top wall 16, or they could be secured to the underside of the top wall 16 independently of the side walls 10 and 12. The essential factor is that the supporting trusses shall be supported so that they are throughout their length slidable relative to the adjacent under surface of the top wall 16. Thus, any tendency for the annealing cover to destroy itself as a result of unequal expansion and contraction between parts rigidly secured together, is completely avoided.

The drawings and the foregoing specification constitute a description of the improved annealing cover in such full, clear, concise and exact terms as to enable any person skilled in the art to practice the invention, the scope of which is indicated by the appended claims.

What I claim as my invention is:

1. An annealing cover comprising side walls, means carried by an opposed pair of side walls adjacent the top thereof cooperating with said opposed pair of side walls to define inwardly open sockets, an elongated top-supporting rigid truss member having its ends slidably positioned in said sockets, and a top wall secured at its edges to the top edges of said side walls, said member being supported wholly by said sockets and independent of said top wall to permit relative sliding between said top wall and said member.

2. A cover as defined in claim 1, and guide means comprising spaced abutments at opposite sides of said truss member carried by the under-

5

side of said top wall longitudinally slidable engageable with the sides of said truss member.

3. A cover as defined in claim 1, said truss member being formed of a metal capable of retaining substantial strength when heated to about 1450 degrees Fahrenheit.

4. A cover as defined in claim 1, said truss member being formed of stainless steel.

5. An annealing cover comprising side walls and a top wall interconnected at their edges, U-shaped brackets located at the juncture between the top edges of said side walls and the side edges of said top wall rigidly secured to one of said walls and forming inwardly open sockets, said brackets being arranged in pairs, top-supporting rigid truss members having their ends slidably supported in said sockets and having upper top-supporting surfaces slidably engageable with the under surface of said top wall.

6. A cover as defined in claim 5, said truss being formed of a metal capable of retaining substantial strength when heated to about 1450 degrees Fahrenheit.

7. A cover as defined in claim 5, said brackets being welded to the top edge portions of said side walls and to the side edge portions of said top walls.

8. An annealing cover comprising wall structure generally including vertical side walls and

6

a flat horizontal top wall rigidly secured at opposite edges to the top edges of said side walls, an elongated top-supporting rigid truss member disposed directly beneath said top wall in slidable supporting relation thereto, truss support means at opposite ends of said truss member secured to said wall structure adjacent the intersection of said side and top walls, said truss support means being constructed to provide rigid support for the adjacent ends of said truss member against vertical movement and at least one of said truss support means being constructed to provide for relative movement between said one truss support means and the adjacent end of said truss member in a direction longitudinal of said truss member.
